Inventor,

Gilbert La Rock

UNITED STATES PATENT OFFICE.

GILBERT LA ROCK, OF ADAMS, NEW YORK, ASSIGNOR TO WYATT A. HAMMOND, OF SAME PLACE.

WAGON-JACK.

SPECIFICATION forming part of Letters Patent No. 295,022, dated March 11, 1884.

Application filed August 10, 1883. (No model.)

To all whom it may concern:

Be it known that I, GILBERT LA ROCK, of Adams, in the county of Jefferson and State of New York, have invented a new and Improved Wagon-Jack for Raising Wheels for Oiling; and I do hereby declare that the following is a full and exact description of the same, reference being had to annexed drawing, in which the figure is a sectional view 10 of my improved wagon-jack.

The nature of my invention is set forth as follows: The lifting-bar is constructed with a groove at A, which is fitted to the end of the lever, (marked B,) to which is attached at C a 15 toggle-joint of iron, which is worked by means of raising or lowering the lever on a joint at D and E, and attached to a key or wedge at F. By the working of the lever B, fitted to the groove at A, the toggle-joint is caused to

move simultaneously and slide the key or 20 wedge under the bottom of the fulcrumed lifting-bar at H (which is cut on a bevel to suit the key) and raise the stepped lifting-bar carrying the wheel to be oiled.

What I claim as my invention, and desire to 25 secure by Letters Patent, is—

The lever B, provided with the toggle-joint D E and wedge F, in combination with the lifting-bar grooved at A, to act as a fulcrum, and provided with steps to receive the weight 30 to be lifted.

The above specification of my invention signed by me this 21st day of July, 1883.

GILBERT LA ROCK.
